UNITED STATES PATENT OFFICE.

JAMES C. SHAW, OF PHILADELPHIA, PENNSYLVANIA, ASSIGNOR TO THE WILLIAM CRAMP & SONS SHIP & ENGINE BUILDING COMPANY, A CORPORATION OF PENNSYLVANIA.

COMPOUND GEARED TURBINE.

1,235,939.

Specification of Letters Patent. Patented Aug. 7, 1917.

Application filed March 29, 1916. Serial No. 87,429.

To all whom it may concern:

Be it known that I, JAMES C. SHAW, a citizen of the United States, residing at Philadelphia, in the county of Philadelphia and State of Pennsylvania, have invented 5 certain new and useful Improvements in Compound Geared Turbine Propulsion, of which the following is a full, clear, and exact specification.

10 This invention relates to marine propulsion, and has for its object to provide a system of compounded geared turbines of separate high and low pressure units in order to improve the economy at both full and reduced powers. The invention is especially 15 applicable to naval vessels, which require to have provision for maximum speed with economy of fuel consumption, and are also required to operate most of the time under 20 economical reduced speeds.

In carrying out the object of the invention, a propeller shaft is provided with a gear, which gear is driven by separate pinions on two or more turbine shafts, each 25 shaft preferably having a high pressure and a low pressure unit, the high pressure unit on one shaft being connected in series with the low pressure unit on the other shaft. At full power, both shafts having a high and a low pressure unit in tandem operate at the 30 same speed to drive the common gear on the propeller shaft, while at reduced powers one high pressure unit and its connected low pressure unit are cut out and run in the condenser vacuum. By proportioning one of 35 the high and low pressure units to take a greater proportion of the total fluid pressure than the other, at least two economical low powers can be obtained, according to 40 which high and low pressure combination is used. In order to enable these two high pressure and low pressure unit combinations to rotate at the same speed under full power while developing respectively different powers when operating alone, one of the low 45 pressure units is made larger than the other, and as herein shown is of the divided flow type in which the sections are equal to each other and also to the other low pressure unit.

50 In such an arrangement, one of the high pressure units and the divided low pressure unit will preferably take two-thirds of the total fluid pressure, while the remaining high pressure unit and the single low pressure unit will take the remaining one-third,

but both units will rotate at the same speed. Of course, other proportions of power consumption can be adopted, but the lower pressure blading in such cases will not be identical. Reversing mechanism is provided at 60 the end of the single low pressure unit, and both of the low pressure units will be connected to a common condenser.

In such an arrangement, the high pressure units and the reverse unit are preferably of all wheel construction, while the low pressure sections are preferably identical in construction and interchangeable, and are ordinarily of all drum construction, although if desired they may be of wheel constructions. The invention also presents a further advantage in that by the provision of three low pressure units the fluid velocity through the last blades can be such as is conducive to best efficiency, thereby permitting 75 of more rugged and shorter exhaust blade design.

The invention will be more fully understood in connection with the accompanying drawing, wherein—

1 represents a propeller shaft having a large gear 2 with which mesh pinions 23, 23, on shafts 24, 25, respectively. The shafts 24, 25, are connected by flexible couplings 9, 10, to shafts 26, 27, which are themselves 85 coupled at 7 and 8, respectively, to the high pressure turbine shafts 28, 29, respectively. On shafts 28 and 26, respectively, are a high pressure all wheel stage unit 3 and a low pressure divided flow, preferably drum stage unit 4 having supply pipes 19, 20, and exhausting into condenser trunk 15 leading to condenser 16. On shafts 29 and 27, respectively, is a high pressure all wheel stage unit 5 and a single flow low pressure unit 6. The low pressure unit 6 is also preferably 90 of drum stages, and is substantially identical with each of the low pressure divided flow stages of the low pressure unit 4. 17 is a reverse turbine in the astern end of low pressure unit 6 and is preferably of all wheel stages similar to the wheels in high pressure units 3 and 5. The exhaust from the high pressure unit 3 is led by pipe 31 to the low pressure unit 6 and the exhaust from high pressure unit 5 is led by pipe 12 to pipes 19 and 20 leading to the divided sections of low pressure unit 4. The main steam supply is by pipe 13 which branches by pipes 30, 35, to the respective high pres- 105

110

sure units 3 and 5. Throttle valves 36, 37 control the supply to the respective high pressure units and 38 is the main shut off valve. For reversing, steam is supplied by pipe 21 to reversing unit 17 through valve 39.

The turbines on either side at full power are preferably run at the same revolutions, so that the pinions are interchangeable.

10 This avoids the necessity of carrying pinions of different sizes either in stock at the yard or on board ship. The power on the two pinions, as well as the revolutions, will be the same when turbines 3 and 6, and turbines 5 and 4, develop equal powers. This will be the case if turbines 3 and 6 each develop one-sixth of the total power, and turbine 5 one-third of the power, and each half of turbine 4 one-sixth of the power. It is 20 permissible, however, to apply more power through one of the pinions than through the other, by changing the proportions. The pinions are duplicates and when operating at reduced power are not stressed to their maximum, being only stressed to their maximum when operating under full power, which is only for a small fraction of the total time the vessel is in operation. Hence the teeth are less liable to breakage, and 30 have longer life than would otherwise be the case. At full power, all the turbines are used and at two-thirds down to approximately one-third power turbines 5 and 4 are used, and the other two revolved in vacuum.

35 At approximately one-third power and less, turbines 3 and 4 are used, and the other two being revolved in vacuum. By having three low pressure turbine parts, the fluid velocity through the last blades can be kept low 40 enough to produce the best efficiency. This also permits of more rugged exhaust blade design and enables stresses due to centrifugal forces to be kept low at the roots of the blades owing to the reduced exhaust blade 45 length. An economy is obtained both in initial cost and in maintenance, as well as in time required for repairs, by having the low pressure sections alike, as herein described. By operating only two turbines at reduced 50 powers, the economy is greatly improved over that where it is attempted to operate all turbines at all times, because in the present invention the blading at both high pressure and low pressure ends is more effective and 55 efficient, even though the other turbines be operated idle in vacuum, than where it is sought to obtain a large range of power by operating all the turbines more or less throttled. Where it is not desired to revolve the 60 idle high pressure turbine in vacuum when operating at reduced power, it is simply necessary to uncouple it at coupling 7 or 8, depending upon which of the high pressure units is being used.

65 The invention is not to be restricted to the

precise construction herein shown as the particular modification here disclosed may be varied without departing from the scope of the appended claims.

Having thus described my invention, I declare that what I claim as new and desire to secure by Letters Patent, is:—

1. In a marine turbine installation, a plurality of shafts each having a high pressure unit and a low pressure unit, a propeller shaft geared to both of said shafts, and means connecting each low pressure unit on one shaft in series with the high pressure unit on the other shaft. 70

2. In a marine turbine installation, a plurality of shafts each having a high pressure unit and a low pressure unit, a propeller shaft geared to both of said shafts, and means connecting each low pressure unit on one shaft in series with the high pressure 80 unit on the other shaft, said respective high and low pressure turbines passing predetermined portions of the total fluid pressure at equal speeds of revolution.

3. In a marine turbine installation, a plurality of shafts each having a high pressure unit and a low pressure unit, a propeller shaft geared to both of said shafts, and means connecting each low pressure unit on one shaft in series with the high pressure 90 unit on the other shaft, said respective high and low pressure turbines passing predetermined unequal portions of the total fluid pressure at equal speeds of revolution. 95

4. In a marine turbine installation, a plurality of shafts each having a high pressure unit and a low pressure unit, a propeller shaft geared to both of said shafts, means connecting the low pressure unit on each shaft in series with the high pressure unit on the other shaft, said respective high and low pressure turbines passing predetermined portions of the total fluid pressure at equal 100 speeds of revolution, and means for obtaining reduced power by cutting out one of said high pressure units and its connected low pressure unit. 105

5. In a marine turbine installation, a plurality of shafts each having a high pressure unit and a low pressure unit, a propeller shaft geared to both of said shafts, means connecting the low pressure unit on each shaft in series with the high pressure unit on the other shaft, said respective high and low pressure turbines passing predetermined unequal portions of the total fluid pressure at equal speeds of revolution, and means for cutting out either of said high pressure units and its connected low pressure unit to secure different reduced powers. 115 120

6. In a marine turbine installation, a plurality of shafts each having a high pressure unit and a low pressure unit, a propeller shaft geared to both of said shafts, means connecting the low pressure unit on each 130

shaft in series with the high pressure unit on the other shaft, and a condenser connected to both of said low pressure units.

7. In a marine turbine installation, a plurality of shafts each having a high pressure unit and a low pressure unit, a propeller shaft geared to both of said shafts, means connecting the low pressure unit on each shaft in series with the high pressure unit on the other shaft, said respective high and low pressure turbines passing predetermined portions of the total fluid pressure at equal speeds of revolution, a condenser connected to both of said low pressure units, and means for obtaining reduced power by cutting out one of said high pressure units and its connected low pressure units independently of said condenser.

8. In a marine turbine installation, a plurality of shafts each having a high pressure unit and a low pressure unit, a propeller shaft geared to both of said shafts, means connecting the low pressure unit on each shaft in series with the high pressure unit on the other shaft, said respective high and low pressure turbines passing predetermined unequal portions of the total fluid pressure at equal speeds of revolution, a condenser connected to both of said low pressure units, and means for obtaining reduced power by cutting out one of said high pressure units and its connected low pressure units independently of said condenser.

9. In a marine turbine installation, a plurality of shafts, one having a high pressure unit and a single flow low pressure unit and the other having a high pressure unit and a divided flow low pressure unit, a propeller shaft geared to both of said shafts, a series connection between each high pressure unit and the low pressure unit on the other shaft, said geared shafts being driven at equal speed at full power.

10. In a marine turbine installation, a plurality of shafts each having a high pressure unit and a low pressure unit, a propeller shaft geared to both of said shafts, and means connecting the low pressure unit on each shaft in series with the high pressure unit on the other shaft, said low pressure sections being bladed alike.

11. In a marine turbine installation, a plurality of shafts, one having a high pressure unit and a single flow low pressure unit and the other having a high pressure unit and a divided flow low pressure unit, a propeller shaft geared to both of said shafts, a series connection between each high pressure unit and the low pressure unit on the other shaft, said single flow low pressure unit and each section of said divided flow low pressure unit being alike.

12. In a turbine installation, a driven shaft carrying a gear, a plurality of driving shafts each geared to said driven shaft

through said gear, a high pressure and a low pressure turbine unit on each shaft in separate casings, each low pressure unit being in series with the high pressure unit on the other shaft and adapted to pass unequal fractions of the total fluid pressure, and controlling means whereby to obtain three powers by using all of said high and low pressure units or one of each.

13. A turbine installation comprising a pair of high pressure turbine units on separate shafts, three low pressure units, two being on one of said shafts and the third on the other shaft, a driven shaft geared to both of said shafts, a series connection to the isolated low pressure unit from the high pressure unit on the other shaft, and a connection between the other high pressure unit simultaneously supplying said remaining two low pressure units.

14. A turbine installation comprising a pair of high pressure turbine units on separate shafts, three low pressure units, two being on one of said shafts and the third on the other shaft, a driven shaft geared to both of said shafts, a series connection to the isolated low pressure unit from the high pressure unit on the other shaft, a connection between the other high pressure unit simultaneously supplying said remaining two low pressure units, and a reversing turbine associated with said isolated low pressure turbine.

15. A marine turbine propulsion system comprising a propeller shaft carrying a gear, a plurality of driving shafts having interchangeable pinions geared thereto, a high pressure and a low pressure unit on one of said shafts, and a high pressure and two low pressure units on the other shaft, a series connection from said first high pressure unit for supplying said two low pressure units on the other shaft in multiple, and a series connection from the other high pressure unit to the remaining low pressure unit.

16. A marine turbine propulsion system comprising a propeller shaft carrying a gear, a plurality of driving shafts having interchangeable pinions geared thereto, a high pressure and a low pressure unit on one of said shafts, and a high pressure and two low pressure units on the other shaft, a series connection from said first high pressure unit for supplying said two low pressure units on the other shaft in multiple, a series connection from the other high pressure unit to the remaining low pressure unit, and a reversing turbine on the shaft carrying the single low pressure unit.

17. A turbine installation comprising a pair of high pressure turbine units, and three low pressure units, one of said high pressure units being in series with one of said low pressure units, the other high pressure unit

- being connected to simultaneously supply the remaining two low pressure units, a shaft carrying one high pressure and one low pressure unit, a second shaft carrying 5 the other high pressure and remaining two low pressure units, one of said shafts having a coupling for disconnecting the high pressure unit, and a propeller shaft geared to both of said shafts.
- 10 18. In a marine turbine installation, a propeller shaft geared to two driving shafts, a high and a low pressure unit on each shaft, one of said high pressure units developing greater power than the other, and one 15 of said low pressure units developing greater power than the other, the low pressure unit of greater power being on the same shaft with the high pressure unit of less power, and connections whereby the total power 20 developed on each driving shaft is equal.
19. In a marine turbine installation, a propeller shaft geared to two driving shafts, a high and a low pressure unit on each shaft, one of said high pressure units developing greater power than the other, and one 25 of said low pressure units developing greater power than the other, the low pressure unit of greater power being on the same shaft with the high pressure unit of less power, and connections whereby the total power 30 developed on each driving shaft is equal at equal speeds of said driving shafts.
20. In a marine turbine installation, a propeller shaft geared to two driving shafts, a high and a low pressure unit on each shaft, one of said high pressure units developing greater power than the other, and one 35 of said low pressure units developing greater power than the other, the low pressure unit of greater power being on the same shaft with the high pressure unit of less power, and connections whereby the total power 40 developed on each driving shaft is equal at equal speeds of said driving shafts.
- 45 the total power developed on each driving shaft at full power is equal.
21. In a marine turbine installation, a propeller shaft geared to two driving shafts, a high and a low pressure unit on each shaft, one of said high pressure units developing greater power than the other, and one 50 of said low pressure units developing greater power than the other, the low pressure unit of greater power being on the same shaft with the high pressure unit of less power, and series connections between 55 the high and low pressure units whereby the total power developed on each driving shaft at full power is equal at equal speeds of said driving shafts.
- 60 22. A turbine installation comprising a driven shaft having a gear, a high and a low pressure turbine in tandem on each side of said gear and connected thereto, cross connections from each high pressure turbine to the low pressure turbine on the other shaft, and means for varying the total power applied to said gear without changing the proportion of power applied on each side.
- 65 23. A turbine installation comprising a driven shaft having a gear, a high and a low pressure turbine in tandem on each side of said gear and connected thereto, cross connections from each high pressure turbine to the low pressure turbine on the other shaft, and means for cutting out one high pressure unit on one side and a low pressure unit on the other side without changing the proportion of power applied on each side.
- 70 In testimony whereof I affix my signature, in presence of two witnesses,

JAMES C. SHAW.
